Primary Examiner—Robert M. Spear*Assistant Examiner*—George D Kirschbaum(74) *Attorney, Agent, or Firm*—Cislo & Thomas, LLP(57) **CLAIM**

The ornamental design for a snail novelty, as shown and described.

DESCRIPTION

This patent application is also related to U.S. patent application Ser. No. 29/221,711, filed Jan. 19, 2005, and which is now issued as U.S. Design Pat. No. D 516,461.

FIG. 1 is a right side elevational view of a snail novelty, in accordance with the present invention.

FIG. 2 is a front view thereof;

FIG. 3 is a top view thereof;

FIG. 4 is a rear view thereof;

FIG. 5 is a left side elevational view thereof; and,

FIG. 6 is a bottom view thereof.

In the drawings, the broken line showing of ears and tail parts depicts environmental subject matter and form no part of the claim.
